Primary Examiner — Dominic V Simone(74) *Attorney, Agent, or Firm* — Kilpatrick Townsend & Stockton LLP**CLAIM**

The ornamental design for a shoe, as shown and described.

DESCRIPTION

FIG. 1 is a front lateral perspective view of an embodiment of a shoe, it being understood that there is no claim being made to the sole.

FIG. 2 is a medial side view of the shoe of FIG. 1.

FIG. 3 is a lateral side view of the shoe of FIG. 1.

FIG. 4 is a front view of the shoe of FIG. 1.

FIG. 5 is a rear view of the shoe of FIG. 1; and,

FIG. 6 is a bottom view of the shoe of FIG. 1.

The broken lines immediately adjacent to shaded areas represent unclaimed boundaries of the claimed design.

The remainder of the shoe shown in broken lines shows unclaimed subject matter only and forms no part of the claimed design.
